US00D997398S

(12) **United States Design Patent** (10) **Patent No.:** **US D997,398 S**
(45) **Date of Patent:** **** Aug. 29, 2023**

(54) **LAMP**

(71) Applicant: **Ningbo Tianqi Intelligent Technology Co., Ltd.**, Ningbo (CN)

(72) Inventor: **Jia Wang**, Ningbo (CN)

(73) Assignee: **Ningbo Tianqi Intelligent Technology Co., Ltd.**, Ningbo (CN)

(**) Term: **15 Years**

(21) Appl. No.: **29/813,486**

(22) Filed: **Oct. 29, 2021**

(51) LOC (14) Cl. **26-05**

(52) U.S. Cl.

USPC **D26/89**

(58) **Field of Classification Search**

USPC ..... D26/24, 26, 51, 72, 76, 81, 83, 85, 87, D26/89, 104, 110, 113, 118-120, D26/123-124; D23/364 CPC .. Y02B 20/40; F21Y 2115/10; F21Y 2113/00; F21Y 2101/00; F21S 8/033; F21S 9/02; F21V 23/0442; F21V 23/0471; F21V 23/023

(57) **CLAIM**

The ornamental design for a lamp, as shown and described.

DESCRIPTION

FIG. 1 is a perspective view of a lamp showing my new design;

FIG. 2 is a front view thereof;

FIG. 3 is a left side view thereof;

FIG. 4 is a right side view thereof;

FIG. 5 is a top plan view thereof; and,

FIG. 6 is a bottom plan view thereof.

The broken lines depict portions of the lamp that form no part of the claimed design.
